D. F. BRODERICK

HYDRAULIC PRESS

Filed Dec. 9, 1926

Fig. 1.

Patented Feb. 26, 1929.

UNITED STATES PATENT OFFICE.

DAVID F. BRODERICK, OF NEW YORK, N. Y.

HYDRAULIC PRESS.

Application filed December 9, 1926. Serial No. 153,519.

My invention relates to hydraulic presses.

The object of my invention is to provide an improved press construction embodying a process for, and means whereby, the packing and rings of a hydraulic press of the character herein described may be so constructed as to permit the easy removal of the ram packing and the replacement of same without the necessity of lifting or re-

10 moving the head of the press.

The type of press to which this invention relates is of the heavy construction high-pressure type which operates to provide a pressure of several thousand pounds per 15 square inch of area over a surface of five or more square feet, and therefore exerting a great tension, five hundred tons or more, on the pillars of the press. By reason of this great tension under load, the pillars 20 are made as short as possible to reduce their stretching, and when the ram packing needs to be replaced the top of the machine must be lifted or dismounted, and the ram and table removed before the flange-rings and 25 packing can be removed from the press.

This operation requires time and skilled labor and is a source of trouble since the press is continued in operation beyond the time that the packing should be changed, 30 resulting in leaks past the packing and preventing a sustained pressure of the required degree from being held in making the matrix for which the press is used.

The present invention overcomes these 35 troubles.

Referring to the drawings which form a part of this specification:

Fig. 1 is an elevational view, partly in section, of a hydraulic press embodying my 40 invention, the ram being shown in its lowest operating position.

Fig. 2 is an elevational sectional view showing the table and piston disconnected and the table raised to permit the removal 45 of the packing ring and packing.

A, indicates a portion of the base casting having a bore A', which is provided with a copper lining B, in which is formed a cylinder C'. A ram C is fitted to reciprocate in said cylinder and its upper end is 50 reduced in diameter and provided with holes D to receive the inner ends of the pins E, which are of less diameter than the holes.

A table F is provided with a bore F' on 55 its under side into which the reduced portion of the ram is loosely fitted and held

to the piston by the pins E, but the thrust of the piston is against the under side of the table and no part of load is carried by the pins. The head G of the press is carried by two steel pillars H—H respectively, circular in cross-section, one of which is located at each side of the table, as shown. The lining B is provided with an annular recess J to serve as a stuffing-box, the top 60 of which is flush with the top surface of the base A. K, indicates the leather packing formed in a ring in the usual manner. L, indicates a metal gland-ring which fits in the stuffing-box to hold the packing in 70 position, and L', indicates a flange-ring which is held in position by stud-bolt and nut construction M. The rings L and L' have heretofore been made integral for presses of this type. I have made them as 75 separate units, so that each ring may be removed from the press through a space large enough to permit the thicker ring L' to pass through after the table has been disconnected from the ram and raised to 80 its highest position, and the ram allowed to descend to its lowest position in the cylinder, as illustrated in Figure 2. By this arrangement I can use very short pillars and can also remove and replace the packing without removing the head G from the press, 85 since it is unnecessary to remove either the table or ram. This is clearly illustrated in Figure 2, the table F being supported in its upper position and the ram lowered to 90 its lowest position, provide a space above the tops of the stud-bolts M and ram C, and under the table, through which the flange-ring L' may be removed laterally, after which the ring L may be lifted and 95 removed and then the packing K may be removed, as will be readily understood. By removing the guide-rods I', one of which is located at each end of the table, by unscrewing them from the lugs I which are 100 formed integral with the table, the table also may be removed from the press without dismounting the head G.

Having thus described my invention, I claim as new:

1. A press of the character described comprising a base having a cylinder therein, a head, pillars connecting said base and head, a ram in said cylinder the upper end of which is no greater in diameter than the body portion thereof and having a length approximately that of the length of the 110

cylinder, a table mounted on the ram in separable relation thereto, a stuffing-box for said ram, a gland ring and a flange ring mounted below said table, and means for holding said flange ring to said base portion.

2. A press of the character described comprising a base having a cylinder therein, a head, pillars connecting said base and head, a ram in said cylinder the upper end of which is no greater in diameter than the body portion thereof and having a length approximately that of the length of the cylinder, a table mounted on the ram in separable relation thereto, a stuffing-box for said ram, a gland ring and a flange ring

mounted below said table, means for holding said flange ring to said base portion, and means for holding said table onto said ram.

3. The construction as set forth in claim 2, and also the following: said means comprising laterally extending pins carried by the table.

4. The construction as set forth in claim 2, and also the following: and means for supporting the table in an elevated position above the ram comprising guide rods carried by the table, and sleeves surrounding said rods supported by said base.

In testimony whereof I affix my signature.

DAVID F. BRODERICK.
